UNITED STATES PATENT OFFICE.

DANIEL McFARLAN MOORE, OF NEWARK, NEW JERSEY, ASSIGNOR TO MOORE ELECTRICAL CO., OF NEW YORK, N. Y., A CORPORATION OF NEW YORK.

AUTOMATIC GAS-FEED FOR VACUUM-TUBES.

968,677.

Specification of Letters Patent. Patented Aug. 30, 1910.

Application filed May 8, 1906. Serial No. 315,728.

To all whom it may concern:

- Be it known that I, DANIEL McFARLAN MOORE, a citizen of the United States, and a resident of Newark, in the county of Essex and State of New Jersey, with post-office address 52 Lawrence street, have invented certain new and useful Improvements in Automatic Gas-Feed for Vacuum-Tubes, of which the following is a specification.
- 10 My invention relates to that class of devices termed vacuum tubes and which are supplied with electrodes or terminals for causing electric energy to pass through the contained gas or vapor.
- 15 The invention is particularly useful for vacuum tube or vapor electric lamps, but may also be applied to vacuum or vapor rectifiers, X-ray tubes, wireless telegraph apparatus or other devices which employ a 20 vacuum through which the electric energy passes.

The object of my invention is to prevent changes in the degree of vacuum due to the passage of the electric energy and consists 25 in an improved means for automatically supplying the gas or vapor of the vacuous spaces so as to maintain the desired gas or vapor tension.

Briefly stated, my invention consists in the 30 combination of a vacuum tube, a manometer connected with the vacuum and means controlled or operated thereby for supplying gas to the tube.

Preferably, I supply the gas by admitting 35 gas in regulated amount from a body of gas of greater tension than that in the tube and for this purpose employ some form of gas valve operated by a manometer.

As a preferred form of valve I use one operating by changes of liquid level, the liquid 40 acting as a seal to shut or open the port or passage through which the gas may feed to the tube, but other forms of valve might be used without departing from my invention.

45 The form shown is described in my prior Patent No. 820364, dated May 8th, 1906, and also in my prior Patent No. 855,801, dated June 4th, 1907.

The manometer employed may be either 50 the form in which liquid is used and the tension of the gas or vapor measured by

differences in the height of a liquid column, or may be of the aneroid type, that is to say, one in which no liquid is used and the pressure or tension is measured by an elastic 55 metal disk or plate or any other form of vacuum pressure gage may be used.

In the accompanying drawings, Figure 1 is a general side elevation and partial section of an apparatus embodying my invention. 60 Figs. 2 and 3 illustrate modifications. Figs. 4 and 5 are other modifications showing a way in which the changes in the position of the parts of the vacuum gage or manometer may be made effective in feeding gas to the 65 tube. Fig. 6 shows another modification. Fig. 7 shows my invention applied to feeding gas away from the tube.

Referring to Fig. 1, a vacuum tube is indicated at 1. The electrodes for supplying 70 electric energy to the gaseous contents are indicated at 2 and are connected with any source of energy as well understood in the art.

The device shown is a form of vacuum 75 tube lamp. The invention, as already stated, is equally applicable to other forms or kind of vacuum tube.

3 is a feed tube through which gas may be fed into tube 1 from any source, and 4 is 80 a valve chamber of any form in which a body of gas at any desired tension greater than that in the tube is maintained. The source of gas may be a tank, or might be the atmosphere, or a gas generator might 85 be connected to the space 4 or air might be passed to such space through phosphorus for the purpose of removing its oxygen when the tube 1 is operated as a lamp. The means for supplying gas to the valve chamber 90 4, however, form no part of my present invention.

The valve shown is of the kind described in by hereinbefore mentioned patent and applications and comprises essentially a 95 plug 10 of some porous material like gas carbon which fits into the end of the gas feed tube 3 and has a pointed terminal adapted to be covered and uncovered by variations in the level of a liquid 5 like 100 mercury in which the plug is immersed as shown. When the tip is uncovered, gas may

- pass slowly from the valve chamber 4 to the tube 3 through the porous material. The changes of level are produced by suitable means operated by the manometer 5 which is connected to the vacuous space in the tube 1. Such connection may be made by means of a tube 6 joined to tube 1 at any desired point. Tube 3 may feed into the tube 1 at one or more points as desired.
- 10 In Fig. 1, 7 indicates a thin corrugated disk of a manometer, one side of said disk being exposed to the variations of gaseous tension in the tube 1 through the connection 6. Various ways of causing the movements 15 of the diaphragm of the manometer to operate the valve may be employed.

In Fig. 1 the operation takes place through the action of an incompressible body of liquid like mercury filling the chamber 8 and the tube 9 which connects chamber 20 8 with the chamber in which the body of mercury 5 rises and falls. To secure a delicate action, the cross sectional area of the space in which the mercury 5 changes its 25 level around the tip of the plug 10 may be very small as compared with that of the body of liquid which is in contact with the diaphragm 7.

In the operation of the apparatus, a 30 lessening of the gaseous tension in 1, owing to the operation of the electric currents upon the contained gas or vapor, causes the diaphragm 7 to move in a direction away from the body of liquid in chamber 8 and this 35 causes the level of the liquid 5 to fall and permit a slight amount of gas to flow through feed tube 3 and restore the vacuum to its normal degree, whereupon the manometer resumes its normal position and the 40 flow stops until a resumption of the action is required.

The manometer might operate the valve in the manner shown in Fig. 2 where the elastic disk or plate 7 is connected directly 45 to a plunger 11 which works in the body of the liquid 5 and by rising, when the tension in the tube 1 decreases, will cause the level of the liquid 5 to fall and thus feed gas to the tube.

50 The tension of the gas in the chamber 4 may be anything desired above that in the tube 1 and may be maintained constantly at such pressure by a suitably adjusted pressure reducing valve interposed, for instance, 55 in the connection from a tank or source of higher pressure which supplies the gas to the chamber 4 as described in prior applications for patent filed by me. Obviously, the pressure in said chamber may be very 60 little greater than that in the tube, so that in the construction shown in Fig. 2, the differences of pressure on the two sides of the diaphragm will be at no time very great.

Moreover, as will be obvious, when a con-

stant pressure is maintained by any means 65 in the chamber 4 the device will not be subject to derangement of action by changes of barometric pressure.

In order to produce a multiplied movement of the valve through any movement 70 of the disk, the plunger or liquid displacer may be made large in comparison with the chamber in which it works or any system of multiplying levers or any devices such as are known in the art for multiplying the 75 movement of the portion of the manometer acted upon by the varying pressure may be employed so as to increase the movement of the device which controls the inlet or outlet for inflow or outflow of gas from the tube. 80

In Fig. 3 a manometer of the liquid form is shown. The tube 12 is connected by an elbow with the chamber in which the level of the liquid changes to open the valve and the liquid in 12 is exposed to the direct 85 action of the gases in the tube 1. As will be obvious, the height of the column 12 will depend upon the gaseous tension in the tube 1.

In Fig. 4, another form of vacuum gage 90 is shown. The tube 12 connects as before directly with the vacuous space and the variations of pressure are measured by the height of the column in the connected tube 13, whose upper end is sealed. The space 95 at the upper end of the tube 13 above the liquid, which may be mercury, is a Torricellian vacuum. This form of manometer may be made of much less vertical dimension than that of Fig. 3. Its movements 100 may be made effective upon the valve by causing the changes of level in 12 to open and close the circuit of any generator of electricity 14, said circuit including the coils of an electromagnet 15 having a core which 105 works in an extension of the valve chamber 4 and is connected to a plunger 11. In this device, the manometer or vacuum gage closes the circuit of the magnet when the gaseous tension in the tube 1 decreases, and 110 the magnet, by lifting the plunger, opens the valve and allows gas to feed to the tube.

In the apparatus shown in Fig. 5, the same action takes place, but the lower end of the tube 12, instead of connecting with a 115 column of liquid having a Torricellian vacuum at its upper end, is simply sealed in a body of liquid contained in the chamber 16 exposed to the atmosphere. This is a form of manometer, which, owing to its 120 large vertical dimensions, is not so well suited to the purposes of my invention as some other forms.

In Fig. 6 the movements of the manometer are transferred to the valve through the 125 intervention of a float which floats in a body of mercury or other liquid of the manometer and is connected, through mo-

tion-multiplying devices of any suitable character as shown, with the plunger 11 and in such way as to open the valve and feed gas to the tube 1 when the tension of the gas therein falls. In case the action of the electric discharge in the tube causes the tension of the gas to increase, gas may be fed out of such tube instead of into it to maintain a constancy of gas tension within the tube, and a normal operation of said apparatus whether used for electric lighting or for any other purpose. Obviously, also the tension of the gas within the tube might be greater than that of the atmosphere and maintained at such greater tension.

Fig. 7 illustrates one of the arrangements of manometer or pressure gage and valve that may be employed in this manner, it being assumed that the pressure within the tube increases during the operation of the lamp, as would be the case with some forms or kinds of tube. In this case, the tube 3 may be connected directly with the atmosphere if the tension to be maintained in tube 1 is greater than that of the atmosphere, or when the tension in the tube 1 is less than that of the atmosphere, there should be maintained in tube 3 and its connections, a gaseous tension less than that of the atmosphere and less than the particular degree of tension or pressure to be maintained in the tube 1.

The plug 10 is located in the body of liquid contained in the pressure gage and in such position that an increase of pressure which results in the lowering of the liquid will expose the tip of the plug to allow gas to pass from the tube 1 and bring its tension back to normal after which the level of the liquid rises and the valve is closed.

What I claim as my invention is:

1. The combination of a vacuum tube, means consisting of the operating portion of a manometer in connection with said tube and means operated thereby for supplying gas to the tube when the gas tension in the tube falls.

2. The combination of a vacuum tube, operating devices of a manometer having a gas connection with said tube and means controlled by said devices for admitting gas to the tube from a body of gas of greater tension than that in said tube when the tension in the latter falls.

3. The combination of a vacuum tube, manometric operative devices subject to the elastic pressure of the gas in the tube and a gas valve controlled by said operative devices for admitting gas to the tube when the gas tension falls.

4. The combination of a vacuum tube, means consisting of the operative portion of an aneroid manometer and means actuated

thereby for admitting gas to the tube when the gas tension falls.

5. The combination of a vacuum tube, a flexible metal disk exposed to the gas or vapor in said tube and means responsive to movements of the disk for admitting gas to the tube.

6. The combination of a vacuum tube, a gas valve operating by changes in liquid level and comprising a body of liquid which opens and closes a gas passage, means consisting of the operative devices of a manometer subjected to the varying gas pressure in the tube, and means connected therewith for producing changes in such liquid level.

7. The combination of a vacuum tube, a gas valve operating by changes of liquid level, means consisting of the operative devices of a manometer connected to the vacuum tube and a chamber in which the liquid rises and falls with the action of said means, the latter chamber and valve chamber being of different cross-sectional area as described to multiply the effect upon the valve of changes of tension in the tube.

8. The combination of a vacuum tube, means consisting of the operative portion of a vacuum gage having its gas pressure space connected to said tube and means controlled by said operative portion for supplying gas to the tube.

9. The combination of a vacuum tube, means consisting of the operative portion of a vacuum gage having its gas pressure space connected to said tube and means controlled by said operative portion for admitting gas to the tube from a body of gas of greater tension than that of said tube.

10. The combination of a vacuum tube, a valve for admitting gas to the tube, means consisting of the operative portion of a vacuum gage whose variable pressure space is connected to the tube, and means for converting the movements of the operative portion into a multiplied movement of the valve.

11. The combination of a vacuum tube, and pressure responsive devices operated by changes in the pressure of the gas within the tube for admitting gas thereto when the pressure falls.

12. The combination of a vacuum tube and means controlled by differences in the mechanical effect of the pressure of gas within the tube for controlling the admission of gas thereto as and for the purpose described.

13. The combination of a vacuum tube, and means mechanically actuated by the varying elastic pressure of the gas within said tube and controlling the flow of gas through a passage connected with said vacuum tube.

14. The combination of a gaseous inclo-

sure through which an electric discharge passes, and means mechanically operated by the force of the elastic pressure of the gas within said tube and controlling the flow of
5 gas through a passage connected therewith as and for the purpose described.
Signed at New York in the county of New

York and State of New York this 5th day of May A. D. 1906.
